United States Patent Office

Des. 214,467
Patented June 17, 1969

214,467

DRAGON BOAT

Shun-Shing Chia, 838 Grant Ave. #7,
San Francisco, Calif. 94108

Filed Apr. 5, 1968, Ser. No. 11,336

Term of patent 14 years

Int. Cl. D12—06

U.S. Cl. D71—1

FIG. 2

FIG. 3

FIG. 4

FIG. 1 is a perspective view of the dragon boat.
FIG. 2 is a side elevational view, the opposite side being substantially a mirror image thereof.

FIG. 3 is a top view.

FIG. 4 is an enlarged sectional view taken along the line 4—4 of FIG. 3 with portions omitted for ease of illustration.

The broken line showing of rudder, sail and mast elements in FIG. 2 is for illustrative purposes only.

I claim:

The ornamental design for a dragon boat, as shown and described.
